CLOSURE AND FASTENER FOR CARTONS

Lewis C. Pennebaker and Leonidas E. Johnson,
Chattanooga, Tenn., assignors to O. B. Andrews
Company, Chattanooga, Tenn., a corporation of
Tennessee

Application May 10, 1951, Serial No. 225,626

2 Claims. (Cl. 229—45)

1

This invention relates to a carton formed of a single sheet of paperboard cut and scored to provide a carton having a top opening that may be closed or opened easily and quickly.

The carton is particularly designed for use as a container for popcorn or similar confections. When popcorn is sold in a theater lobby the sales must be made quickly during the rush between shows or between acts, and time lost in setting up boxes causes loss of sales because prospective customers generally will not wait to buy the popcorn if the waiting will make them miss part of the performance. It is often impractical to set up a sufficient number of cartons before the rush to take care of the sales because of the space required. Even if the cartons are set up in advance, it is often impossible for the clerk to take the time to close the top of the carton, and the result is that popcorn is spilled by patrons carrying it to their seats in unclosed cartons. In accordance with the present invention the cartons are stacked in flat folded condition, the bottom is arranged so that it will snap into proper position when the sides of the carton are pressed from the flat form into tubular form, and the top is adapted to be quickly and securely closed after filling.

It is an object of this invention to provide a carton with a top that may be closed quickly and efficiently and yet may be easily reopened by the consumer. It is a further object to provide a carton with a top that may be closed again by the consumer if the contents are not all consumed.

Additional objects and advantages of the invention will become apparent upon reading the following description, taken in conjunction with the accompanying drawings showing a preferred illustrative embodiment of the invention, in which:

Fig. 1 is a perspective view of a closed carton embodying the invention;

Fig. 2 is a perspective view of the carton shown in Fig. 1 showing the bottom;

Fig. 3 is a fragmentary perspective view showing the upper portion of the carton with the top in open position;

Fig. 4 is a fragmentary cross sectional view showing the cut and score lines at one side of the upper portion of the carton;

Fig. 5 is a view, similar to Fig. 3, showing the top of the carton partially folded;

Fig. 6 is a view, similar to Fig. 3, showing the top of the carton as it approaches closed position;

2

Fig. 7 is a fragmentary cross sectional view showing the top of the carton in closed position;

Fig. 8 is a fragmentary cross sectional view showing the top closure flap being snapped into closed position;

Fig. 9 is a fragmentary cross sectional view showing the top closure flap in closed position; and

Fig. 10 is a plan view of the blank from which the carton is formed.

Referring to Fig. 10 of the drawings, the blank comprises a single sheet of paperboard cut and scored to provide back and front wall panels 2 and 3 respectively, side wall panels 4 and 5, and glue flap 6, which are foldable along score lines 7, 8, 9 and 10. During the manufacturing operation the blank is folded on score lines 7 and 9 and flap 6 is adhered to panel 3 in any suitable manner.

The bottom of the carton may be formed in any suitable manner. As illustrated, however, it is formed by flaps 11, 12, 13 and 14 which are separated from panels 2, 3, 4 and 5 by score lines 15, 16, 17 and 18, respectively. The flap 11 is provided with a recess 19 disposed centrally of its free edge, and the flap 12 is provided with a tongue 20 adapted to interlock with the recess 19 when the bottom of the carton is set up. A score line 21 extends diagonally of flap 11 from one end of the score line 15 to the edge of recess 19, and a similar score line 22 extends diagonally of flap 12. The corner portion 23 of flap 11 set off by the score line 21 is adhered to flap 14 and the portion 24 of flap 12 set off by the

score line 22 is adhered to the flap 13. When portions 23 and 24 are adhered respectively to flaps 14 and 13, the score lines 21 and 22 permit the bottom of the carton to be formed in flat position with the flaps folded against the interior surfaces of the wall panels and with the tongue 20 offset laterally from the recess 19. When the sides of the carton are pressed from flat to tubular form, the tongue 20 registers with the recess 19 and the inherent resilience of the paperboard causes flaps 11, 12, 13 and 14 to move towards a common plane with the bottom interlocked by the interengagement between the tongue 20 and recess 19.

The top of the carton comprises a flap 25 separated from panel 2 by a score line 26, and a narrow flap 27 separated from panel 3 by a score line 28. A web 29 connects the adjacent edges of panel 5 and flaps 25 and 27 and is separated from panel 5 by a score line 30, from flap 25 by a score line 31, and from flap 27 by

a score line 32. The score lines 30 and 31 are perpendicular to each other and the triangular portion of tab 29 is bisected by score line 33 so that when flap 25 is folded along score line 33 the web 29 comprises two triangular portions superimposed and projecting outwardly beyond fold line 31 and constitute a composite triangular tab. The smaller triangular portion 34 of tab 29 folds between the superimposed triangular portions of the tab when the flap 27 is folded at right angles along score line 28 and the flap 25 is subsequently folded along score line 26.

A web 35 similar to the web 29 but reversed thereto is provided on the opposite side at the upper edge of panel 4. Since the structure at each side of the top of the carton duplicates the structure at the opposite side, except for the reversal of directions, only one side of the top will be specifically described. A plurality of diagonal cut lines 36 and 37 provided in the upper edge portion of panel 5 are intersected by a cut line 38 parallel to score line 36 to form a portion 39 of substantially the same area as the area of tab 29 when it is folded except for the extreme tip portion. A slit 40 extends outwardly from cut line 38 to form two flaps 41 and 42.

When the carton is to be closed the flap 27 is folded inwardly along the line 28 and the flap 25 is then folded inwardly along the line 26 so that the tabs 29 and 35 project outwardly with the portions 34 interposed between the triangular portions of the tabs 29 and 35. The composite tabs 29 and 35 are then pressed downwardly and inwardly. The slit 40 permits the flaps 41 and 42 to flex so that the corner of tab 29 can be pushed past the panel 5. The flaps 41 and 42 then move back to their normal position and the tabs 29 and 35 are interlocked with panels 5 and 4, respectively, because the end of the tab projects below the cut line 38. It is to be noted that while the tabs 29 and 35 move or swing downwardly into position within the opening defined by the cut lines 36 and 37, the generally trapezoidal portions 39 which normally fill the openings yield and swing inwardly of the carton and upwardly against the flaps 27 and 25 which assume a horizontal position and constitute a composite top wall for the closed carton. In other words, the portion 39 may be said to be displaced by the tabs 29 and 35 during closure of the carton.

The flap 25 facilitates filling the carton because it projects beyond the edge of flap 27 when the carton is set up with its top open. The carton with its top open can be pushed into a large receptacle containing popcorn and the flap 25 acts as a lip to hold enough popcorn so that the carton will be substantially filled in one motion. The flaps 25 and 27 are then folded inwardly and the tabs 29 and 35 pressed downwardly and inwardly to close the carton. Although flaps 41 and 42 hold the end of the tabs 29 and 35 securely so that the top will not open accidentally, it is necessary only to grasp the front edge of flap 25 and raise it upwardly to move the tabs 29 and 35 to open position.

During filling of the carton in the manner set forth above and after the same is filled, but before the carton is closed, the trapezoidal portions 39 fill the opening provided by the cut lines 36 and 37 and prevent egress of the popcorn

kernels from these openings. During closing of the carton and while the portions 39 swing inwardly and upwardly as previously explained, the popcorn kernels are "backed up" so to speak and pushed away from the opening until the portions 39 have been displaced by the oncoming flaps 29 and 35. Thus at no time is there any leakage or spilling of the popcorn.

While the foregoing specification sets forth a preferred embodiment of the invention in considerable detail, many changes may be made in the construction without departing from the spirit of the invention, and it is therefore desired that the present embodiment be considered in all respects as illustrative and not restrictive, reference being had to the appended claims rather than to the foregoing description to indicate the scope of the invention.

We claim:

20. 1. A tubular carton having front, back and side walls, a top flap foldably joined to each of said front and back walls, the top flap joined to said back wall being of sufficient length to extend substantially completely across said carton and the top flap joined to said front wall being relatively short and adapted to underlie the outer portion of said back wall top flap when both are folded inwardly at right angles to said front and back walls, a first triangular web portion joined to the top of each of said side walls along a hinge line, second triangular web portions foldably joined to said back wall top flap and to each of said first web portions, and third triangular web portions foldably joined to said front wall top flap and to each of said first web portions, said first and second web portions at each side of said carton being of substantially equal size and adapted to overlie one another when said back wall top flap is folded down to form an outwardly folded composite tab, said tabs being triangular and having said hinge lines as their bases, each of said side walls being provided with a cut extending from one side edge thereof to the other and comprising sections converging toward each other from the ends of said hinge line and a central section parallel to said hinge line to form therefrom a truncated triangular tab based on said hinge line, said composite tabs having sufficient length so that they are adapted to displace said truncated triangular tabs inwardly and to engage said side walls below said cuts to hold said front and back wall top flaps folded down to form a closure for said carton.
55. 2. A tubular carton as defined in claim 1 wherein a second cut extends downwardly from the middle of said central section.
